US0D1060226S

(12) **United States Design Patent** (10) **Patent No.:** **US D1,060,226 S**
(45) **Date of Patent:** **** Feb. 4, 2025**

(54) **CHARGING PILE**

(71) Applicant: **NIO TECHNOLOGY (ANHUI) CO., LTD**, Hefei (CN)

(72) Inventors: **Jingyang Yao**, Shanghai (CN); **Kechao Li**, Shanghai (CN); **Fan Wu**, Shanghai (CN); **Nikhil Banwaskar**, Shanghai (CN); **Kris Tomasson**, Munich (DE); **Colin Phipps**, Shanghai (CN); **Shiyi Hang**, Shanghai (CN); **Qiuchen Weng**, Shanghai (CN); **Long Sheng**, Shanghai (CN); **Lijian Xia**, Shanghai (CN); **Zhiqian Zhuang**, Shanghai (CN)

(73) Assignee: **NIO TECHNOLOGY (ANHUI) CO., LTD**, Hefei (CN)

(**) Term: **15 Years**

(21) Appl. No.: **29/869,252**

(22) Filed: **Dec. 27, 2022**

(30) **Foreign Application Priority Data**

Jun. 28, 2022 (CN) 202230401079.4
Dec. 9, 2022 (CN) 202230827539.X

(57) **CLAIM**

The ornamental design for a charging pile, as shown and described.

DESCRIPTION

FIG. 1 is a perspective view of a charging pile showing our new design;

FIG. 2 is a front elevation view thereof;

FIG. 3 is a left side elevation view thereof;

FIG. 4 is a right side elevation view thereof;

FIG. 5 is a rear side elevation view thereof;

FIG. 6 is a top plan view thereof; and,

FIG. 7 is a bottom plan view thereof.

The broken lines in the drawings are for the purpose of illustrating portions of the charging pile that form no part of the claimed design.

1 Claim, 3 Drawing Sheets
